[57] CLAIM

The ornamental design for a garment attachable patch, as shown and described.

DESCRIPTION

FIG. 1 is a front elevational view of a garment attachable patch showing my new design in use, the broken lines showing a pullover being for illustrative purposes only and forming no part of the claimed design; FIG. 2 is an enlarged front elevational view thereof; FIG. 3 is a right side elevational view of FIG. 2; FIG. 4 is a rear elevational view of FIG. 2; FIG. 5 is a left side elevational view of FIG. 2; FIG. 6 is a top plan view of FIG. 2 shown rotated 180 degrees; and, FIG. 7 is a bottom plan view of FIG. 2, shown rotated 180 degrees.
